UNITED STATES PATENT OFFICE.

LOSEY J. WILLIAMS, OF BELOIT, WISCONSIN.

TIGHTENING DEVICE FOR CLOTHESLINES OR THE LIKE.

1,360,846.

Specification of Letters Patent.

Patented Nov. 30, 1920.

Application filed January 21, 1920. Serial No. 353,036.

To all whom it may concern:

Be it known that I, LOSEY J. WILLIAMS, a citizen of the United States, residing at Beloit, in the county of Rock and State of Wisconsin, have invented certain new and useful Improvements in Tightening Devices for Clotheslines or the like; and I do hereby declare the following to be a full, clear, and exact description of the invention, such as will enable others skilled in the art to which it appertains to make and use the same.

The present invention relates to improvements in tightening devices for clothes lines or the like, and has for an object to provide an improved device capable of quick and convenient application to a clothes line for the purpose of taking up the slack therein.

Another object of the present invention resides in providing a device of this character for carrying out the above described purposes which will be simple in construction and designed for simple manipulation, and which will be cheap in manufacture.

In the accompanying drawings forming a part of this application, and in which similar reference symbols indicate corresponding parts in the several views:

Figure 1 is a side elevational view, with one end broken away, of an improved tightening device constructed in accordance with the present invention;

Fig. 2 is a cross sectional view taken on the line 2—2 in Fig. 1;

Fig. 3 is a similar view taken on the line 3—3 in Fig. 1; and Figs. 4 to 9, inclusive, are diagrammatic views showing various stages of applying the improved tightening device to a clothes line or the like.

Referring more particularly to the drawings, wherein only a single mechanical embodiment of the invention is illustrated, 1 designates a handle made of any suitable material or length, and having the rectangular cross section shown in Figs. 2 and 3, although any other cross section desirable may be used, as this forms no essential part of the invention.

The handle 1 is provided at one end with a groove 2 in which the clothes line is received, although any other means to receive the clothes line may be used. A hook 3 provided with a threaded shank 4, or other suitable securing means, is fastened in the handle 1 near the opposite end thereof and projects downwardly, the mouth of the hook 3 being open as shown in Fig. 2.

The handle 1 also carries a rack 5 along

its lower edge in proximity to the grooved end 2, but this rack may extend along the entire lower edge or throughout any portion thereof desired, or may be placed on the upper edge, or on either side, or any other means may be employed to accomplish the same purpose. This rack 5 is preferably made of a piece of wrought iron bent or waved in the manner best illustrated in Fig. 1 and having its ends perforated to receive screws 6 and 7, by which the rack is secured to the handle 1. It is obvious, however, that other securing means may be used. Adjacent the secured ends the rack is formed with depending loops 8 and 9 which form stops to limit the movement of the frame 10 which embraces the handle 1 and is slidable and adjustable along the same, the lower portion of the frame 10 being receivable into the notches of the rack 5.

The frame 10, as shown in Fig. 3, is rectangular and advantageously made of metal. It is slightly larger than the cross section of the handle 1, so that said frame 10 may be raised to the vertical position, whereby the lower portion thereof may clear the teeth on the rack 5, permitting the frame 10 to be shifted along the handle 1 to the desired position. It is obvious that the frame may be made of any suitable material, or combination of materials, and that it may be made in any other suitable form to perform its functions, said functions being the holding of a device for engaging the line, of being easily moved from point to point along the handle, and of engaging with means on the handle for holding said frame securely at any desired point along the handle. It is also obvious that to perform the above functions the shape of the frame is not essential, that it may be only partly inclosed, or may be in a T or other form, the shank passing through the handle either perpendicularly or horizontally, and, by engaging with the rack, or other means, be adjustable along the handle.

The frame 10 carries at one side thereof an arm 11 from which projects a pin 12 carrying a grooved wheel 13 held thereon as by a cotter pin 14. The wheel 13 is open on the side opposite the arm 11 for allowing the device to be engaged with a clothes line indicated at 15. It is obvious that a hook or other means may be attached to or made part of the frame 10 in place of the arm 11, the pin 12, the grooved wheel 13 and the cotter pin 14, and that such hook or other

means may accomplish substantially the same results.

The application of the device to a clothes line is shown in Figs. 4 to 9, inclusive. As shown in Fig. 4, the handle 1 is placed beneath the line 15 and the line is engaged with the grooved wheel 13, the line passing on the under side of said wheel.

Referring to Fig. 5, the handle 1 is next 10 rotated about the grooved wheel 13 in a clockwise direction whereby the grooved end 2 of the handle 1 is brought beneath and engaged with the line 15.

In Fig. 6 the grooved end 2 of the handle 15 1 is shown fully engaged with the line 15, and forms a bight therein.

Fig. 7 shows a slightly further position of the handle 1.

The final position of the device is shown 20 in Fig. 8, where the hook 3 is shown engaged over the line 15 after the handle 1 has been rotated to the final position. The device forms a bight in the clothes line 15, taking up the slack therein; and in accordance with 25 the amount of the slack to be taken up, the frame 10 carrying the grooved roller 13 is adjusted along the handle 1.

In Fig. 9 is also shown a view similar to Fig. 8 with the handle reversed, showing 30 how it may be applied by engaging it over the clothes line instead of beneath the same and rotating the handle in a counter-clockwise direction. The effect here, however, is the same as in the first mentioned case.

From the foregoing it will be appreciated 35 that I have provided an exceedingly simple, cheap and effective device for the purpose of tightening or taking up slack in clothes lines or the like.

It is obvious that those skilled in the art 40 may vary the details or materials of construction and arrangements of parts without departing from the spirit of my invention, and therefore I do not wish to be limited 45 to such features except as may be required by the claims.

I claim:

1. A tightening device for clothes lines and the like including a handle adapted to be placed intermediate of the line and to be supported wholly by the clothes line, means disposed between the ends of the handle for initial engagement with the clothes line and adapted to form a center about which the handle may be rotated on the line to form 50 a bight therein, said handle being provided at one end with means in which to receive the bight of the line, and means projecting laterally from the handle at the opposite end thereof and at the side opposite from said first mentioned means whereby to receive the line to support the handle therefrom after it has been rotated to produce said bight, substantially as described.

60 2. A tightening device for clothes lines and

the like including a handle, an adjustable roller projecting laterally from one side of said handle and adapted to be initially engaged over an intermediate portion of the clothes line to support the tightening device 70 from the line, said handle having a groove made in one of its ends to receive the line when the handle is rotated about such roller as a center, the line engaging in said groove being formed into a bight, and a hook projecting laterally from the handle and from the side thereof opposite to that in which the roller projects, said hook being at the end of the handle opposite said groove whereby to receive the line and to hold the handle 80 against rotation in the reverse direction, substantially as described.

3. A tightening device for clothes lines or the like including an elongated thin handle, a rack secured to said handle and having 85 stops at its ends, a frame fitted about said handle and movable into and out of the notches in said rack, a roller carried by said frame and adapted to be initially engaged with an intermediate portion of the clothes line, said handle having a groove formed in 90 its end adjacent said roller to receive and form a bight in the line when the handle is rotated about the roller as a center, said handle adapted to be brought parallel with the line, said stops adapted to hold the line away from said rack, and a hook at the other end of said handle opposite the grooved end 95 for finally receiving the line and for holding the handle against rotation in a reverse direction, substantially as described.

4. A tightening device for clothes lines or the like comprising an elongated thin wooden handle having a groove made in one end thereof, a metallic thin corrugated bar 105 forming rack teeth secured to one side of said handle, said bar being looped outwardly away from the handle near its opposite ends to form stops at each end of the rack, a rectangular frame fitting loosely about said handle and being tiltable thereon, said frame adapted to engage the teeth of the rack bar to hold the frame in adjusted position, a roller carried by said frame and adapted to be initially engaged with an intermediate 110 part of the clothes line, said handle adapted to be rotated about the roller as a center to direct the clothes line into the grooved end of said handle whereby to form a bight 115 therein, said handle adapted to be swung to a position parallel with the clothes line extending from said bight, said stops adapted to space the line from the rack and from said frame, and a hook at the end of the handle opposite said grooved end and projecting in a direction oppositely with respect to said roller for finally engaging the line to prevent reverse rotation of the handle, substantially as described.

LOSEY J. WILLIAMS.
